CLOCK CASING

Giacinto C. D'Ercoli, Park Forest, Roger L. Kelly, Arlington Heights, and Ellsworth R. Danz and Roman J. Szalek, La Salle, Ill., assignors to General Time Corporation, Stamford, Conn., a corporation of Delaware

Filed July 19, 1967, Ser. No. 7,885

Term of patent 14 years

(Cl. D42—7)

FIG. 1

FIG.2

FIG.3

FIG.4

FIG.6

FIG.5

FIG. 1 is a front perspective view of a clock casing showing our new design;

FIG. 2 is a rear perspective view;

FIG. 3 is a top plan view;

FIG. 4 is a front elevational view;

FIG. 5 is a rear elevational view; and

FIG. 6 is a left side elevational view.

The broken line showings are for illustrative purposes only.

We claim:

The ornamental design for a clock casing, substantially as shown and described.
